W. W. TAYLOR,
MOP OR BRUSH HANDLE,
APPLICATION FILED NOV. 18, 1908.

Patented Apr. 13, 1909.

UNITED STATES PATENT OFFICE.

WILLIAM WALLACE TAYLOR, OF GIRARD, PENNSYLVANIA.

MOP OR BRUSH HANDLE.

No. 917,908.

Specification of Letters Patent. Patented April 13, 1909.

Application filed November 18, 1908. Serial No. 463,153.

To all whom it may concern:

Be it known that I, WILLIAM WALLACE TAYLOR, residing at Girard, in the county of Erie and State of Pennsylvania, have invented certain Improvements in Mop or Brush Handles, of which the following is a specification.

The present invention relates to handles for grasping and retaining articles such as brushes, cloths or masses of strings or rope employed in mops, dish-washers, dusters, etc.

The objects of the invention are to provide ready and adjustable means whereby the variety of articles and materials employed for the purposes enumerated may be secured, held, and quickly released when necessary; and secured in such a manner that none of the parts composing the said means shall come in contact with the objects upon which the article held, such as a mop or duster portion, is being used, so that the objects shall not be scratched, bruised or injured in any way. All of which I will now proceed to describe and point out in detail, reference being had to the accompanying drawings, in which—

Figure 1 is a perspective view of an embodiment of the invention. Fig. 2 is a partial section of another application of the invention. Fig. 3 is a partial section representing the previous figure turned one-quarter way around. Fig. 4 is a section on line $x-x$ of Fig. 3; and Figs. 5 and 6 represent different constructions of a detached member.

In the drawings a is a handle provided at its lower end with a ferrule b extending beyond the same and having its end c reinforced. Located in the lower end of the ferrule and rotatable in the same is a hub g having a hollow cup-shaped end i said hub being provided with a narrow slot h extending longitudinally through the same. The lower end of the handle a has a hole p extending longitudinally therein, and d is a metal nut inserted into the handle having a screw-thread registering with the said hole; and e is a threaded rod adapted to pass into the hole p and be held in position by the nut d through which it extends, and its lower end is flattened and terminates in a hook f . Some portions of the hook and the flattened portion are located in the slot h of the hub at all times and said hook is thus prevented from

rotating as the screw or handle is turned, as herein described. The rod e and its flattened portion constitute the shank of the hook.

In the application of the invention represented in Figs. 2, 3, and 4, A represents a cloth, a mass of parallel strings or rope through the central part or bight m of which extends or is looped the fibrous endless band j , the opposite ends of which are held on the hook. When the cloth, etc., is to be attached to the handle the cup end i is held firmly and the handle turned, thus causing the screw-threaded part to traverse the nut and the hook to be projected from the end of the cup a sufficient distance, when the loop j (having been passed through the center or bight m of the cloth; etc.) has its ends placed over the hook, and then the handle is turned in an opposite direction until the bight of the cloth is drawn up into the cup tightly and the utensil is ready for use as a floor mop, dish-washer, or for any purpose to which it may be applied. A string k about the cloth secures the upper part of the same and gives form to the same.

The metal piece r may be used instead of the fibrous band j if preferred, and when employed it is passed through the cloth, its ends looped up about the same and the holes $2, 2$, placed over the hook and then drawn up into the cup as before described. It will be observed that the upper end of the cloth s forms a cushion, so that when the device is used, say for a mop, there can be no scratching or abrasion of the floor, or when used as a duster there will be no destruction or injury of the most delicate article.

The figure 1 represents the application of the handle to a floor brush. In this case I prefer to secure to the back of the brush B a hemi-spherical member t , provided at its upper side or back with means for connection with the hook f of the handle, which may be an eye o in the member, to which the hook is directly connected, or a loop j or r may be employed. By this arrangement the handle is held firmly to the part t about which it may move, after the manner of a universal joint.

As will be seen this device provides a means for securely holding a variety of articles, which may be easily and quickly detached. There is great flexibility in the

adjustment of the hook to a variety of thicknesses of cloth, etc., so that no particular sizes will have to be employed.

I do not limit myself to the precise details shown in the drawings, as they may be widely departed from and still embody the spirit of my invention.

I claim as my invention—

The combination with a handle having a longitudinal hole and a fixed nut, of a ferrule secured to the handle and extending beyond its end, a hub rotatably mounted in the end of the ferrule and having a longitudinal slot and provided with a cup-shaped portion be-

yond the end of the ferrule, and a hook having a shank a portion of which is threaded and engaged by said nut, another portion being flattened to engage the walls of the slot of the rotatable hub.

In testimony whereof, I have signed my name to this specification in the presence of two subscribing witnesses, this 11th day of November 1908.

WILLIAM WALLACE TAYLOR.
